UNITED STATES PATENT OFFICE.

MARION E. GIBSON, OF PORTLAND, OREGON.

STERILIZING-CABINET.

1,190,541.

Specification of Letters Patent. Patented July 11, 1916.

Application filed October 28, 1914. Serial No. 869,049.

To all whom it may concern:

Be it known that I, MARION E. GIBSON, a citizen of the United States, residing at Portland, in the county of Multnomah and State 5 of Oregon, have invented a new and useful Sterilizing-Cabinet, of which the following is a specification.

This invention relates to new and useful improvements in sterilizing cabinets.

10 An object of the present invention is to provide a cabinet which may be used by doctors, dentists, etc., for the purpose of sterilizing instruments, bandages, and similar materials.

15 A further object is to provide a cabinet with a plurality of compartments so arranged that the materials inserted within the compartments may be subjected to a dry heat, steam, or a germicidal and disinfecting gas, or any combinations thereof.

20 Another object is to accomplish the aforementioned ends in a simple and efficacious manner and to so arrange the apparatus as to be simple in construction, cheap to manufacture, and capable of utilizing steam.

25 With the foregoing and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without departing from the spirit of the invention.

35 In the drawings accompanying this specification and forming a part thereof, the preferred embodiment of my invention is illustrated, in which:

40 Figure 1 is a side view in elevation of my improved sterilizing cabinet with portions thereof broken away to more clearly disclose the arrangement and disposition of parts. Fig. 2 is a front view in elevation of the 45 same. Fig. 3 is a fragmental view in section, illustrating the two upper compartments and the glass shelving which is slidably disposed in the lower one. Fig. 4 is a detail view in section of the floor locking 50 mechanism.

Referring to the drawings in which similar reference numerals designate corresponding parts throughout the several views, a cabinet or casing 4 is formed of some suitable 55 material such that it will be air tight, withstand the corrosive action of germicidal

gases, and will possess a sanitary and neat appearance.

The cabinet is provided with the transversely extending partitions 5 and 6 which 60 divide the cabinet into the upper compartment C¹, the central compartment C² and the lower compartment C³. It is to be noted that the number of sizes of the compartments may be varied, according to the class 65 of service the sterilizing cabinet is to perform. The upper compartment C¹ is provided with a door 7 and latch 8 so that it may be held in a tight condition and hermetically sealed. The compartment C² is 70 provided with a similar door 9 and latch 10 for similar purposes.

The lower compartment C³ has what is termed a boiler B disposed therein and which includes the two spaced shells 11 and 12. 75 The front wall has a door 13 hingedly secured by the arms 14. The door is provided with a concentric rim 15 through which the slots 16 extend. A holding band 17 is secured to and extends around the 80 upper surface of the rim as illustrated in Fig. 2. Pivottally and rotatably secured to the door is the hand wheel and shaft 18 to which is secured the plate or spider 19. A plurality of resilient arms 20 are carried by 85 the plate 19 and project through the slots 16 in the rim and are adapted to engage beneath an overhanging rim 21 with which the front wall of the compartment is provided. Thus when the hand wheel is rotated in one 90 direction, the curved and flexible arms 20 will be moved inwardly tending to straighten and will be extended beneath and rigidly grip the overhanging rim 21, thus securely locking the door in a closed and hermeti- 95 cally sealed condition.

It will therefore be noted that the cabinet or casing has a circular opening leading to the boiler, and that the door 13 is seatable against the outer side of the casing within 100 the annular overhanging rim 21 with which the outer side of the casing is provided around said opening. The spider 19 is disposed upon the outer side of the door, and said door has guides, as above indicated, for 105 the arms of the spider adjacent the margin of the door, the terminals of the spider arms being projected behind said rim by the screw 18 which is engaged with the door and hub of the spider.

The space defined between the inner and outer shells of the boiler is adapted to re-

ceive steam or other heating medium there-
in which is supplied thereto by the pipe
23 for whose control the valve 24 is ar-
ranged. An outlet pipe 25 communicates
5 with the steam receiving receptacle 22 and
is provided with the usual and conventional
type of thermal vacuum valve 26. The
boiler is thus arranged to receive steam
either in a normal or superheated condition
10 which will result in the heating of the boiler
to the desired temperature and impart heat
to the adjacent parts of the cabinet. In
order that the interior of the shell 11 may
receive the live steam therein so that articles
15 within the same may be subjected to the
moist heat of steam, the pipe 23 is provided
and is controlled by the valve 24. The pipe
in question extends between and communi-
cates with the steam receiving receptacle
20 22 and the interior of the shell 11.

Arranged directly above the boiler B and
within the compartment C³ is the gas gen-
erator 29 which is in the form of a recep-
tacle, communicating with which is the pipe
25 30. The pipe 30 extends through the front
wall of the cabinet and is closed by a cap
31, thus providing for the introduction of a
liquid or other material whose heating will
result in the production of a germicidal or
30 disinfectant vapor or gas. Communicating
with the gas generator 29 is the outlet pipe
32 which communicates with a distributing
coupling 33 so that the gas is directed to
the boiler B or upper compartment. Com-
35 municating with the outlet pipe 32 are the
supply pipes 34 and 35 leading to the upper
compartment and each of which is independ-
ently controlled by the valves 36, thus pro-
viding for the independent introduction of
40 germicidal and disinfecting gases or va-
pors within the said compartments. A pipe
38 communicates with the gas line and is
provided with the controlling valve 37 by
means of which the interior of the shell 11
45 is supplied with any desired quantity of
gas or is shut off from the supply.

The compartment C² is provided with a
50 number of angle brackets 39 for the support
of the detachable glass shelving 40. The
shelving is disposed within the compart-
ment as a matter of convenience and to in-
crease the capacity of the compartment for
the retaining of surgical instruments and
other articles which it is desired to expose
55 to the germicidal gases and dry heat. The
boiler is adapted to heat the various com-
partments and thus expose the articles dis-
posed therein to a dry heat. Thus the cab-
inet may be used to advantage in barber
60 shops for the heating of towels as well as the
sterilization of the various implements. The
gas generator is positioned directly above
and thus utilizes the heat of the boiler for

the generation of the gases with the result
that the gases will be in active state due to
65 the fact that they are highly heated. The
various doors of the respective compart-
ments being hermetically sealed, prevents
the escapement of the noxious and steriliz-
70 ing gases and the valves provide for the tem-
porary closing of the gaseous supplies to the
compartments during the time the doors are
opened for either the removal or insertion of
75 the various articles. The boiler B being sur-
rounded by a steam receiving receptacle may
be heated to a high temperature correspond-
ing to the pressure of the steam which cir-
culates therein. A pressure gage 41 indi-
80 cates the pressure within the steam receiving
receptacle and therefore indirectly indicates
the thermal condition of the boiler. The
pipe 26 allows the live and moist steam to be
85 inserted directly within the inner shell and
thus in actual contact with such articles
as may be placed therein. This allows for
the heating of what is known as wet towels
used in barber shops and for similar pur-
90 poses. The means whereby the door 13 is
held closed, allows a certain amount of pres-
sure to be retained within the interior of the
95 shell 11 without forcing the door outward
or resulting in the escapement of steam
therethrough. The boiler may also be pro-
vided with the disinfecting gases in addition
to the steam as will be readily apparent.

Having thus fully described my invention,
what I claim to be new and original with me
and desire to secure by Letters Patent, is:—

In a device of the character described, a
casing having a circular opening and an an-
nular overhanging rim surrounding said
opening upon the outer side of the casing, a
circular door adapted to rest against the
outer side of the casing within said rim
to close said opening, a resilient dished
100 spider upon the outer side of the door, the
door having guides for the arms of the
spider adjacent the margin of the door, the
105 terminals of the spider arms being project-
able beyond the margin of the door to en-
gage behind said rim, and a screw engaged
with the door and hub of the spider whereby
said screw can be rotated for forcing said
hub toward the door, thereby tending to
move the spider arms into a common plane,
110 to project said arms behind said rim, the
spider when released bending away from
115 the door.

In testimony that I claim the foregoing as
my own, I have hereto affixed my signature
120 in the presence of two witnesses.

MARION E. GIBSON.
